UNITED STATES PATENT OFFICE.

GURDON H. WILLIAMS, OF GREENSBURG, OHIO, ASSIGNOR OF ONE-HALF
TO ALBERT A. RAYMOND, OF SAME PLACE.

DEVICE FOR CUTTING AND SCREW-THREADING WAGON-AXLES.

SPECIFICATION forming part of Letters Patent No. 317,694, dated May 12, 1885.

Application filed March 26, 1884. (No model.)

To all whom it may concern:

Be it known that I, GURDON H. WILLIAMS, of Greensburg, in the county of Trumbull and State of Ohio, have invented certain new and useful Improvements in Devices for Cutting and Screw-Threaded Wagon-Axes; and I do hereby declare the following to be a full, clear, and exact description of the invention, such as will enable others skilled in the art to which it pertains to make and use the same.

My invention relates to improvements in devices for cutting and screw-threading wagon-axes; and it consists in certain features of construction and in combination of parts hereinafter described, and pointed out in the claims. The boxing in the hub of a wagon-wheel, when the parts are new, should fit snugly endwise between the back shoulder on the axle and the nut in front. As the parts become worn, there is considerable end-play between the axle and the said boxing in the hub of the wheel, that is for various reasons objectionable. The nut when "screwed up" butts against the outer shoulder of the axle. In order to take up the lost motion, this shoulder is cut farther back and the thread cut farther on the axle, and to make a finished job the end of the axle should be dressed off, so as not to protrude through the nut. My improved apparatus furnishes a simple and effective means of doing such work.

In the accompanying drawings, Figure 1 is a view in side elevation, and Fig. 2 a longitudinal section, of my improved device. Figs. 3 and 5 are perspective views of the face of the respective milling burrs or tools. Fig. 4 is an end view of the thread-cutting device.

A represents the body of the device. It is circular in cross-section, and the larger end is provided with a cylindrical bore, in which operates the revolving cutter-head B. The bore of the smaller end is threaded to engage the feed-screw C, that is provided with the hand-wheel c. This screw is provided with a central longitudinal bore, through which passes the spindle D, that is secured at the inner end to the cutter-head B, so that the two parts will turn together in either direction. The outer end of the spindle is provided with the crank E, secured by the set-screw e. The hub of the crank and one end of the cutter-head

butt, respectively, against the outer and inner ends of the feed-screw C, so that the end motion of the spindle and attached cutter-head is governed entirely by the said feed-screw. 55 The inner end of the cutter-head is provided with a recess, into which the tools F, G, and H are successively inserted as required.

I are yielding arms secured to the outside of the part A, and are provided at their other ends with the clamping block or jaws J, that are adapted to grasp the axle, and are operated by the screw K of the yoke L, by means of which the part A is held rigidly endwise on the axle. 60

The cutting-tools are each provided with a hole or groove, and the cutter-head B is provided with a dowel-pin, b², or equivalent device, for entering said hole or groove on the respective cutter-tools, by means of which the tool is caused to revolve with the head B. The tool F, which is first inserted, having a central bore, slips over the threaded part of the axle, and its face is provided with teeth that engage the shoulder on the axle. By means of 70 the feed-screw C and the hand-wheel c a pressure is brought to bear, forcing the tool against the said shoulder, and as the tool is rotated by means of the said crank, connecting-spindle, and cutter head, the shoulder is quickly 75 cut back the required distance. Next, the tool F is removed and replaced by the tool G, that

is simply a screw-threading die of the variety known as "solid dies." These dies are made right and left handed, and of proper size and 80 lead of thread to fit the threads already on the ends of the axle. In operating these dies by 85

the crank E, the hand-wheel c should be turned so as to follow up the die in its engagement with the thread of the axle until the die reaches 90 the new face of the shoulder. By this means a continuation of the former thread is cut still farther, so that the nut of the axle may be screwed up until it butts against the newly-cut shoulder. Next, the tool H is placed in 95 position. This tool is a solid block with a slightly-concaved end provided with teeth, and is operated in a similar manner to the tool F, by means of which the end of the axle is dressed off, so as not to protrude through the 100 axle-nut when the said nut is "screwed home."

By means of the flexible arms I the machine,

while held rigidly endwise, may move more or less laterally, so that the cutting-tools may adjust themselves to the axle.

The machine is simple, durable, and effective, and weighs only a few pounds, so that it may be easily handled and operated. When one end of the axle is raised to remove the wheel for oiling the bearing, if it is found that there is end-play, after the wheel is removed it requires but a few moments to dress the axle in the manner described, so that the parts will fit as well as when new.

What I claim is—

1. In a device for cutting and threading wagon-axles, the combination, with the body or part A and a cutter-head arranged in said body, of flexible arms secured to said body, and provided with clamping devices adapted to grasp the axle and hold the body, with its inclosed parts, rigidly against endwise movement, substantially as set forth.

2. In a device for cutting and screw-threading wagon-axles, the combination, with a rotating cutter-head provided with a recess at the inner end, and provided with suitable mechanism for revolving the same and feeding it endwise, of cutter-tools adapted, respectively, to cut the shoulder on the axle, to dress

the end of the axle, and to cut the thread farther on the axle, and made interchangeably to fit the said recess in the cutter-head, substantially as set forth.

3. In a device for cutting and threading wagon-axles, the combination, with the body or part A and a cutter-head arranged in said body, of flexible arms secured to said body, blocks secured to the free ends of the arms, and a yoke and set-screw for locking the blocks to the axle, substantially as set forth.

4. In a device for cutting and threading wagon-axles, the combination, with the body or part A and devices for securing said body to the axle, of the cutter-head located within the body, a spindle secured to the cutter-head and provided on its outer end with a crank, and the feed-screw surrounding the spindle and resting at its inner end against the cutter-head, and provided at its outer end with a hand-wheel, substantially as set forth.

In testimony whereof I sign this specification, in the presence of two witnesses, this 6th day of March, 1884.

GURDON H. WILLIAMS.
